UNITED STATES PATENT OFFICE.

ERNST FUES, OF HANAU-ON-THE-MAIN, GERMANY.

ABSORBENT-MATERIAL-SIZING COMPOSITION.

1,276,206.

Specification of Letters Patent. Patented Aug. 20, 1918.

No Drawing.

Application filed June 15, 1914. Serial No. 845,321.

To all whom it may concern:

Be it known that I, ERNST FUES, a subject of the German Emperor, and resident of Hanau-on-the-Main, Germany, have invented certain new and useful Improvements in Absorbent-Material-Sizing Composition, of which the following is a specification.

My present invention relates to a new method of sizing absorbent material, particularly paper, in a single operation, by soaking it with a mixture of certain solutions and then drying.

I have made the observation that soaps are not precipitated from their solutions by acids or acid salts, if such solutions contain at the same time a certain quantity of animal size. In the course of my experiments on the subject I have found that particularly colloidal substances possess the said property of preventing precipitation. The substances which, according to my present invention, are suitable for that purpose will, therefore, in the following specification be termed briefly as "protective colloids".

My invention, which is based on the aforesaid observation, consists in operating the sizing of absorbent material by means of a mixture of various solutions which contain the following:

(a) Precipitable sizing-agents, for instance solutions of fatty acids or rosin acids, shellac, albumen, casein or the like;

(b) Substances having the property of preventing precipitation of the sizing-agents and thus acting as "protective colloids", for instance animal size, gum arabic or the like;

(c) Precipitants, for instance alum, sulfate of alumina, and other acid salts or acids, or the like.

These mixtures are almost entirely clear—sometimes somewhat opalescent—if they are prepared in the proper proportion which must, of course, be varied according to the kind and number of components used, and for which, with due regard to the variations caused by local conditions, no standard can be given. The mixtures contain the sizing agents in an ultramicroscopically fine state and must be regarded as so-called "pseudo-solutions" rather than as proper solutions.

If, for instance, unsized paper is dipped in a solution as above described (for instance in a solution composed of rosin-size, animal-size and sulfate of alumina) and, after squeezing, dried in the usual manner

over drying-cylinders, the paper will be perfectly and quite evenly sized, this requiring only a portion of the quantity of size necessary when using the ordinary method of rosin-sizing the paper-pulp while it is in the beater. This may be easily understood considering the extraordinary fineness of the particles of the size in the "pseudo-solution", and considering the fact that by this method of sizing with "protective colloids" any losses of the material are entirely avoided.

Another advantage of this new sizing method is that it gives satisfactory results, even if water-hardening agents, such as Ca- or Mg-salts, are present, which would render the ordinary method of rosin-sizing impracticable.

The process may be applied either to any entirely finished (unsized) paper or to paper while it is made on the paper machine. In either case the disadvantage of repeatedly having to moisten and dry the finished paper is only an apparent one, which is counterbalanced, if not outweighed, by the great advantages which offer the working of unsized paper on the paper-machine. These advantages are quite obvious and consist in the fact that the whole wet-part of the paper-machine (strainer, wirecloth, screens and felts) are much less soiled and blocked than in cases where sized paper is worked and that the screens and felts are kept in good condition for a longer time and, thereby interruptions of working avoided, although the paperweb is more rapidly drained and dried (at higher temperature) whereby it is possible to accelerate the working and produce larger quantities of paper in a given time.

The method of sizing with "protective colloids" is of particular advantage in the sizing of hand-made paper, because it effects a considerable saving of animal-size, and moreover it is superior in regard to the stability of the size-mixture as compared with the pure animal-size used with other methods. Moreover the hand-made papers sized according to the new process can be more rapidly dried than those sized with animal size.

The new method can be utilized with advantage not only in the manufacture of papers and card-boards, but also in the preparation of any other absorbent material, for instance for the impregnation of fabrics

or the like, which could hitherto be effected only in two separate consecutive operations, namely by first dipping the material in the soap-solution and subsequently treating the 5 product thus prepared with alumina salts.

According to my new process the impregnation is effected in a single operation which renders the whole process considerably cheaper.

10 In further developing the idea underlying my invention, I have found that it is technically possible to combine with the above described sizing-method a dyeing process, namely by adding dyestuff solutions to the 15 sizing liquid. The "protective colloids" contained in the sizing-liquid possess the peculiar property of rendering it possible to use simultaneously dyestuffs belonging to different classes which, in absence of the 20 "protective colloids," would be precipitated by each other; thus a green color can be obtained by simultaneously using a basic yellow and an acid blue dyestuff as an admixture to the sizing liquid.

25 Claims:

1. An absorbent material sizing composition containing a sizing medium precipitable by acid substances, acid precipitating means, and a small quantity of a suitable protective 30 colloid, for the purpose described.

Copies of this patent may be obtained for five cents each, by addressing the "Commissioner of Patents, Washington, D. C."

2. An absorbent material sizing composition containing a vegetable sizing medium precipitable by acid substances, said precipitating means, and a small quantity of a suitable protective colloid, for the purpose de- 35

3. An absorbent material sizing composition containing a sizing medium precipitable by acid substances, acid precipitating means, and a small quantity of animal size, 40 for the purpose described.

4. An absorbent material sizing composition containing a sizing medium precipitable by acid substances, acid precipitating means, a dye stuff, and a small quantity of a suitable protective colloid, for the purpose de- 45

5. An absorbent material sizing composition containing a sizing medium precipitable by acid substances, acid precipitating means, 50 dye stuff, and a small quantity of animal size, for the purpose described.

In testimony whereof I have signed my name to this specification in the presence of two subscribing witnesses.

ERNST FUES.
